SPOON

Mildred L. Wendling, Portland, Oreg.

Application April 13, 1948, Serial No. 145,676

Term of patent 14 years

(Cl. D44—29)

To all whom it may concern:

Be it known that I, Mildred L. Wendling, a citizen of the United States, residing at Portland, in the county of Multnomah and State of Oregon, have invented a new, original, and ornamental Design for Spoons, of which the following is a specification, reference being had to the accompanying drawing, forming part thereof.

Figure 1 is a perspective view of a spoon, showing my new and ornamental design.

Figure 2 is a plan view.

Figure 3 is a side view.

Figure 4 is an end view looking into the lip end of the spoon.

I claim:

The ornamental design for a spoon, as shown.

MILDRED L. WENDLING.
